CLAIM

The ornamental design for a top sizer for a garment hanger, as shown and described.

DESCRIPTION

FIG. 1 is a front elevation view of a top sizer for a garment hanger showing our new design;

FIG. 2 is a front elevation view thereof;

FIG. 3 is a rear elevation view thereof;

FIG. 4 is a left side elevation view thereof;

FIG. 5 is a top plan view thereof;

FIG. 6 a right side elevation view thereof;

FIG. 7 is a partial front elevation view thereof; and,

FIG. 8 is a partial rear elevation view thereof.

FIGS. 2 through 8 are shown on an enlarged scale.

The broken lines shown in the drawing disclosure are for illustrative purposes only and form no part of the claimed design.
